UNITED STATES PATENT OFFICE

2,571,037

ADJUSTABLE HAMMOCK HANGER

Frederick P. Hoffman, Dade City, Fla.

Application February 13, 1948, Serial No. 8,239

1 Claim. (Cl. 5—128)

1

This invention relates to new and useful improvements and structural refinements in hangers for hammocks, and the principal object of the invention is to provide a hammock hanger which may be quickly and easily adjusted so as to accommodate hammocks of various lengths.

A further object of the invention is to provide a hammock hanger which may be easily and conveniently transported from one location to another.

Another object of the invention is to provide a hammock hanger which is equipped with an overhead shade and with side trays to accommodate newspapers, beverage glasses, and the like.

An additional object of the invention is to provide a hammock hanger which is simple in construction, which will not easily become damaged, and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a top plan view of the invention without the overhead cover or shade;

Figure 2 is a side elevational view thereof;

Figure 3 is a cross sectional view, taken substantially in the plane of the line 3—3 in Figure 1;

Figure 4 is a cross sectional view, taken substantially in the plane of the line 4—4 in Figure 1;

Figure 5 is a cross sectional view, taken substantially in the plane of the line 5—5 in Figure 2;

Figure 6 is a side elevational view of the invention including a supporting framework for the overhead shade;

Figure 7 is a top plan view of the framework shown in Figure 6, and;

Figure 8 is a cross sectional view, taken substantially in the plane of the line 8—8 in Figure 7.

Like characters of reference are employed to designate like parts in the specification and throughout the several views.

Referring now to the accompanying drawings in detail, more particularly to Figures 1—5 inclusively, the invention consists of a hammock hanger designated generally by the reference character 15, the same embodying in its construction a pair of substantially U-shaped supports 16 disposed in spaced parallel relation and each

2

including a horizontal mid-portion 17 and upright end portions 18.

Integral cross bars 19 connect together the upright portions 18 at both ends of the supports 16, while one or more additional cross bars 20, 21 may be provided to connect the mid-portions 17 of the supports, as is best shown in Figure 1. Two of these last mentioned cross bars (20) assume the form of axles for pairs of travelling wheels 10 22, whereby the entire hanger may be easily and conveniently transported from one location to another.

A plurality of eye hooks 23 are provided on the cross bars 19, which eye hooks are adapted to engage the usual eyes or loops, or the like, 24 provided on a hammock 25 for suspension purposes, the hammock itself of course being of any suitable construction and not constituting a component of the invention.

20 It will be apparent from the foregoing that the hammock will be effectively supported by the hanger, and means are provided for adjusting the hanger so as to accommodate hammocks of different types.

25 Said means reside in the formation of each the supports 16 in two sections divided medially the length of the portions 17, the adjacent ends of the sections being adjustably connected together by means of tubular couplings 26. Each of these couplings is rigidly secured at one end thereof to one section of the support by means of a transversely extending bolt and nut assembly 27, while the end portion of the remaining section is slidably telescoped in the coupling, wherein it may be adjustably secured by means of a set screw 28. Accordingly, by simply loosening the set screws 28 and sliding one section of the mid-portions 17 in the couplings 26, the overall length of the hanger may be adjusted as desired, so as to accommodate hammocks of various lengths.

30 For reinforcement purposes the upright portions 18 of the supports 16 may, if desired, be provided with suitable tie rods 29, and it will be also noted that a plurality of spaced, superimposed service trays or racks 30 are provided adjacent one end of the hanger on one of the supports 16. The trays 30 are simply mounted upon a pair of carriers 31 formed from bars or rods, said carriers being rigidly secured to the mid-

35 portion of one of the supports 16.

40 The purpose of the trays 30 is, of course, to accommodate magazines, books, beverage glasses, and the like.

45 Referring now to the accompanying Figures 55 6—8 inclusively, the hanger 15 illustrated herein

is, in all respects, similar to the hanger already described, but is equipped with an overhead framework for supporting a cover or shade above the hammock.

This framework includes in its construction a pair of inverted L-shaped rods 32 which are secured at one end thereof to the aforementioned cross bars 19 and extend toward each other, being adjustably connected together at their remaining ends by means of a tubular coupling 33, similar to the aforementioned coupling 26.

The rods 32 are equipped with a plurality of transversely extending, arcuate beams 34 which are secured to the rods 32 by bolts, or the like, 35, and it will be noted that the outer ends of the beams 34 are similarly secured as at 36 to a pair of longitudinally extending side pieces 37. The side pieces are also formed in two sections and are adjustably connected together by means of further tubular couplings 38, and the outer ends of the side pieces are connected together by transverse, straight end bars 39.

Inasmuch as the bars 39 are straight while the beams 34 are arcuated, a cover or shade (not shown) which is to be supported by the framework will have a rounded configuration at its ends. Moreover, inasmuch as the side pieces 37 are disposed at a lower level with respect to the rods 32 (by virtue of the arcuate beams 34) the longitudinal side portions of the shade or cover will also be rounded.

Needless to say, by adjusting the couplings 33, 38 the overall length of the framework may be varied to conform to the overall length of the hanger 15, after each adjustment of the couplings 26.

It is believed that the advantages and use of the invention will be clearly apparent from the foregoing disclosure and accordingly, further description thereof at this point is deemed unnecessary.

While in the foregoing there has been shown and described the preferred embodiment of this

invention it is to be understood that minor changes in the details of construction, combination and arrangement of parts may be resorted to without departing from the spirit and scope of the invention as claimed.

Having described the invention, what is claimed as new is:

A shade support for hammocks, comprising an inverted U-shaped frame affording a horizontal bight portion and a pair of downwardly extending legs secured at the lower ends thereof to a hammock support, a plurality of transverse arch beams secured at the center thereof to said bight portion at longitudinally spaced points on the latter, a pair of parallel rails disposed at relatively opposite sides of and substantially below said bight portion and secured to the ends of said beams, said rails extending at both ends beyond the respective ends of said bight portion, and a pair of straight cross bars connecting together the ends of said rails exteriorly of said legs, whereby a shade secured to said rails and said cross bars may be downturned at all marginal edge portions thereof.

25 FREDERICK P. HOFFMAN.
